UNITED STATES PATENT OFFICE

WILLIAM WHEELER, OF BROOKLYN, NEW YORK

INTERNAL-COMBUSTION ENGINE

Application filed December 10, 1928. Serial No. 153,742.

This invention relates to internal combustion engines and my improvements are directed particularly to an engine possessing novel features of construction with means 5 adapted for the vaporization of heavy hydrocarbon oils without subjecting the formed gaseous mixture to the influence of excessive temperatures.

It is well understood that high speed, low 10 compression engines are ill suited to the efficient combustion of heavy oils because the degree of heat necessary to gasify the fuel thins the attendant air and thereby diminishes the weight of the charge. Since the 15 temperature of the mixture must be maintained during its passage from the carburetor to the intake, to prevent coalescence of the fuel, the difficulties in the way of introducing a well proportioned mixture of heavy 20 hydrocarbon fuel and air have heretofore remained unsolved.

Therefore it is the object of my invention 25 to cause the liquid fuel to be subjected to a relatively high temperature in a passageway between the carburetor and intake, and to provide in the same passageway a flow path or duct heated at a relatively lower temperature for the travel of the mixture of gasified fuel and air to the intake, said gaseous mixture path or duct being adapted to deliver 30 by gravitation any fuel in liquid form into the more highly heated passageway, and also being adapted to receive back into the flowing gaseous mixture the liquid fuel that 35 has become vaporized in said more highly heated passageway.

Hence my invention consists, broadly expressed, in subjecting the liquid fuel alone to a temperature at which it will become vaporized, and as vaporized permitting it to mix 40 with a proportionate volume of air in a path or duct which is heated only to a point at which the fuel will be held in a gaseous state while flowing to the engine intake. In this manner I am enabled to put into the engine a gaseous charge of full weight for efficient 45 combustion.

Other features and advantages of my invention will hereinafter appear.

In the drawings:

Figure 1 is a side elevation of an engine embodying my improvements.

Figure 2 is a top plan view thereof, partly in section.

Figure 3 is a side elevation, taken from the 55 side opposite that shown in Figure 1.

Figure 4 is an end view, enlarged, partly 60 in section on the line 4-4 of Fig. 3.

Figure 5 is a partial side sectional view 65 of the fuel gasifying chamber with the mixture passageway extended therethrough, also showing the three-way control valve.

Figure 6 is a horizontal section of the 70 three-way valve, shown open for delivery of gasoline and air mixtures.

Figure 7 is a similar view with the valve 75 open for delivery of oil and air mixtures.

Figure 8 is an enlarged sectional detail view on the line 8-8 of Figure 1, showing the exhaust manifold and its relation to the 80 mixture drying chamber.

Figure 9 is a plan view of the heating element employed in the fuel gasifying chamber.

Figure 10 is a longitudinal view, showing 85 in vertical section the interior of the mixture drying chamber, with its baffles and relation to the exhaust manifold.

Figure 11 is a horizontal section through 90 the mixture heating chamber and the drying chamber, taken on the line 11-11 of Figure 1.

Figure 12 is a cross-section through the 95 mixture heating chamber and a spark plug chamber therein, and

Figure 13 is a plan view of a heating element employed in conjunction with the 100 spark plug chamber.

In the Figures let 1 indicate an engine block provided with the cylinders 2, the intake manifold 3, exhaust manifold 4, and cooling jacket 5.

Two carburetors are herein shown, one of them, indicated at 6, being intended for the use of gasoline for engine starting purposes and receiving its supply as from a vacuum tank 7. This carburetor communicates direct with the intake manifold in the usual manner. The other carburetor, indicated at 8, is supplied with heavier liquid fuel as from a vacuum tank 9, and communicates with a mixture heating chamber 10 that is imposed 105

upon the engine block and extends lengthwise thereof. The passageway between carburetor 8 and chamber 10 is here shown at 11 as connecting with one end of said chamber.

5 The engine block is provided with the usual threaded orifices for spark plugs, and its upper surface has cup-shaped depressions 12 about these orifices, the chamber 10 having like cup-shaped depending portions 13 that fit within depressions 12.

10 Instead of fitting spark plugs directly in the threaded orifices as is the usual practice, I fit therein the hollow devices 14 which I call 15 spark plug chambers, said devices having the lower tubular neck portion 15 to fit in the spark plug orifices 15' and the upper tubular portion 16 that is interiorly threaded to receive a spark plug 17. The tubular portion 20 16 is also exteriorly threaded to engage a threaded opening in a cover plate 16' that closes an opening 10' in the top of chamber 10 of sufficient size for the introduction and removal of the spark plug chamber. The 25 intermediate portion of the device 14 is radially enlarged and its upper surface has an annular trough formation 18. The troughs 18 and cups 13 are intended to collect fuel that deposits therein in a liquid state, so that such 30 fuel may become gasified through the heat generated in the spark plug chambers. Also a resistance wire 19, carried by an insulation member 20 that is supported within a spark plug chamber may be energized by a source 35 of electrical energy forming part of the engine equipment (not herein illustrated) to supply heat for vaporizing the collected oil in trough 18.

40 The spark plug chambers 14, which receive the gaseous charges of compressed fuel mixture for ignition generate great heat that within these chambers promotes combustion and facilitates flame propagation throughout the combustion chambers. But as these chambers 45 14 extend into the mixture heating chamber 10 they are subjected to the influence of the cool air that is drawn in from the carburetor and passes contactingly over them in its passage, whereby a desirable heat exchange is 50 effected between said chambers and passing stream of fuel and air mixture, serving to reduce the temperature of the chambers while raising the temperature of the mixture.

55 Disposed alongside the engine block, extended lengthwise thereof and of the mixture heating chamber 10, is a drying chamber 21 which receives the fuel and air mixture after it has traversed the length of heating chamber 10. Since the opposed walls of chambers 10 60 and 21 are placed close together communication between them is provided by means of an orifice 22 through the juxtaposed walls near the end thereof distant from the supply communicating means 11, so that the fuel and air mixture must travel through the length of

chamber 10 before entering chamber 21. The drying chamber is supplied with heat from the exhaust manifold. As a convenient and desirable means of applying heat from the exhaust to chamber 21 I provide said chamber with the transverse sleeves 22', into which are fitted the tubular extensions 23 of the exhaust manifold, these extensions 23 having abutting relation with manifold pipe sections 23'; suitable packing 24 serving to seal the joints. Lugs 26 formed at the sides of the sleeves 22 are provided with holes 27 for the reception of bolts 25 which are used to secure the drying chamber 21 and heating chamber 10 together and to the manifold.

70 The drying chamber is provided with baffles 29, here shown as extended upwards from the sleeves 22' toward but in spaced relation from the top of said chamber. Now it will be noted that whereas the inlet 22 to the drying chamber, located at one end of said chamber, is in a plane above the tops of the baffles, the exit from chamber 21 indicated at 30 as located at the other end of said chamber, is disposed in a plane below the tops of the 80 baffles. The reason for this arrangement is as follows: It is intended that the fuel which remains in suspension shall flow with the air in a nearly direct path from inlet 22 to outlet 30, while the heavier fuel particles may 85 be caught by the baffles and if sufficiently liquid will flow downwardly toward the sleeves 22'. As the sleeves become highly heated by the exhaust manifold and communicate some of their heat to the baffles it is 90 evident that any liquefied fuel contacting therewith will become gasified and again enter the stratum of fuel mixture flowing toward outlet 30. Said outlet 30 communicates with a pipe or conduit 31 which extends to 100 and communicates with a valve that controls the admission of fuel mixture into the intake manifold. In the drawings this valve is shown as a three-way valve 32 with control connection 32', adapted to open communication 105 to the intake manifold both from the gasoline carburetor 6 and from the conduit 31, but serving to close one of these supply sources while the other is open. Conduit 31 is shown as enclosed in a boxlike structure 110 33 that is rectangular in cross-section, the sides of the box fitting snugly against said conduit, but the top and bottom of the box being spaced from the upper and lower surfaces respectively of the conduit, thereby providing the clearances 34, 35. The upper portion of the conduit is pierced with apertures 36, and its lower portion is pierced with apertures 37. Now it will be apparent that any fuel in a liquid state entering the conduit 115 31 along with the flowing gaseous mixture, or forming therein due to coalescence of fuel particles, will pass by gravitation through the apertures 37 into the clearance 35, so 120 that no fuel in liquid form will enter the in- 125

take manifold. But the liquid fuel falling into clearance 35 is to be gasified and caused to re-enter in gaseous state the stream of fuel mixture flowing through conduit 31. Therefore I provide heating means in the clearance 35 suited to gasify the liquid fuel passing thereinto. As shown I provide for this purpose a resistance wire 38 carried by an insulation member 39 which is suitably supported upon the base of box 33, the terminals of said resistance wire being suitably included in an electrical circuit (not shown). The fuel thus gasified in clearance 35 is drawn into conduit 31 under the influence of the suction pull of the engine, a curved pipe 40 being here shown as extended from clearance 35, through the lower portion of conduit 31 and having an issuance nozzle lying in the path of the stream of gaseous mixture flowing toward the engine intake.

The upper clearance 34 is shown as provided with an air inlet 41, controlled by a valve 42 which is held normally closed by means of a spring 43. The stem 44 of this valve lies in the down path of an armature 45, pivoted to a bracket 46 mounted on box 33, with adjustment means 47, said armature being actuatable by an electro-magnet 45' that is included in a circuit (not shown), said armature when actuated serving to depress the stem 44 and thereby to open the valve. By means of this valve auxiliary air may be admitted to clearance 34 through inlet 41 and thence will be drawn into the conduit 31 through apertures 36 under the aspiratory pull of the engine.

From the foregoing description of parts and their functions it will be appreciated that I, realizing the differences in temperatures needed for gasifying heavy liquid hydrocarbon fuel and for holding together a mixture of air and gas generated from such fuel, have provided passageways for the mixture which are subjected to heat that is insufficient in temperature to effect an undue attenuation of the air in the mixture, and other passageways for the fuel while it is in a liquid state, said other passageways being subjected to heat at a temperature adapted to convert such liquid fuel into a gaseous state. Further, as will also be noted, liquid fuel that becomes gasified in the troughs 18 and cups 13 then passes into the mixture flowing through the heating chamber 10; similarly, liquid fuel that becomes gasified by contact with the baffles 29 and sleeves 22 then passes into the mixture flowing through the drying chamber 21, and finally liquid fuel that becomes gasified in clearance 35 then passes into the mixture flowing through the conduit 31.

Variations within the spirit and scope of my invention are equally comprehended by the foregoing disclosure:

I claim:

1. An internal combustion engine adapted

for the combustion of relatively heavy hydrocarbon fuel, said engine having an intake manifold and a passageway directing a flowing stream of fuel and air mixture to said manifold, a mixture heating chamber included in said passageway, and spark plug chambers located in said heating chamber to effect a heat exchange therewith.

2. An internal combustion engine adapted for the combustion of relatively heavy hydrocarbon fuel, said engine having an intake manifold and a passageway directing a flowing stream of fuel and air mixture to said manifold, a mixture heating chamber included in said passageway, spark plug chambers located in said heating chamber to effect a heat exchange therewith, and troughs in said heating chamber to collect liquid fuel leaving the flowing mixture stream, said fuel being gasified by electrical heating means.

3. An internal combustion engine adapted for the combustion of relatively heavy hydrocarbon fuel, said engine having an intake manifold and a passageway directing a flowing stream of fuel and air mixture to said manifold, a mixture heating chamber included in said passageway, spark plug chambers located in said heating chamber to effect a heat exchange therewith, and depressions in said spark plug chambers to collect liquid fuel leaving the flowing mixture stream to gasify the fuel by the heat generated within said spark plug chambers.

4. An internal combustion engine adapted for the combustion of relatively heavy hydrocarbon fuel, said engine having an intake manifold and a passageway directing a flowing stream of fuel and air mixture to said intake manifold, a drying chamber, a fuel gasifying chamber in communication with said drying chamber, electrical heating means provided at the base of said chamber, a duct included in said passageway and extended through said gasifying chamber, said duct provided with apertures for the gravity delivery of liquefied fuel into said gasifying chamber, and means for conveying gasified fuel from said chamber into the stream of mixture flowing through the duct.

5. An internal combustion engine adapted for the combustion of relatively heavy hydrocarbon fuel, said engine having an intake manifold and a passageway directing a flowing stream of fuel and air mixture to said manifold, a mixture heating chamber included in said passageway, spark plug chambers located in said heating chamber to effect a heat exchange therewith and heating means associated with said chambers for gasifying the fuel in said heating chamber.

6. An internal combustion engine adapted for the combustion of relatively heavy hydrocarbon fuel, said engine having an intake manifold and a passageway directing a flowing stream of fuel and air mixture to said

manifold, a mixture heating chamber included in said passageway, spark plug chambers located in said heating chamber to effect a heat exchange therewith, an auxiliary air chamber, means of communication between said passageway and chamber, said auxiliary air chamber having an inlet and controlled means to regulate the supply of air through said inlet.
